UNITED STATES PATENT OFFICE.

FREDERICK H. BEROLD, OF WYOMING, OHIO.

TRIPPING MECHANISM FOR PRINTING-PRESSES.

1,357,945.

Specification of Letters Patent.

Patented Nov. 9, 1920.

Application filed October 30, 1916. Serial No. 128,506.

To all whom it may concern:

Be it known that I, FREDERICK H. BEROLD, a citizen of the United States, residing at Wyoming, in the county of Hamilton and State of Ohio, have invented certain new and useful Improvements in Tripping Mechanism for Printing-Presses, of which the following is a specification.

My invention relates to mechanism for tripping the impression-cylinder in printing presses and is applicable in so-called flat-bed presses as well as in presses employing a rotary type or plate cylinder or cylinders. I have exemplified my invention as applied to a rotary printing press.

It is the object of my invention to provide a printing press comprising an impression-cylinder which is normally in off-impression relation to the printing surface, and is arranged to be held in on-impression relation to the printing surface, and mechanism whereby the impression-cylinder is caused to approach the path of the printing surface at each revolution of the impression-cylinder whether the impression-cylinder be rotating in off-impression or in on-impression relation to the printing surface; further to provide manually controlled means whereby the impression-cylinder is maintained in printing position and whereby, further, the impression-cylinder is released from printing or on-impression position into normal off-impression position.

It is the object of my invention further to provide gripper-mechanism and to so relate the impression-cylinder tripping means as to insure the proper gripping of the sheet for proper registry thereof at each revolution of the impression-cylinder, so that the sheet is received properly about the impression-cylinder, whether the impression-cylinder at the revolution thereof at which the sheet is taken is in printing or in off-impression relation; in order, among other things, that the sheet may be properly printed, and may be properly delivered into the sheet-delivery mechanism regardless of whether the sheet has been printed or not.

It is the object of my invention further, to provide novel means for tripping an

impression-cylinder making one revolution to an impression, enabling the printing throughout at least half the circumference of the impression-cylinder and also causing positioning of the impression-cylinder in exact sheet-taking position at each revolution thereof for taking the sheet, whether the impression-cylinder be tripped or untripped.

It is the object of my invention further, to provide novel means, exemplified as an eccentric mounting for the impression-cylinder and a quick-acting cam control for the eccentric, comprising a part for causing movement of the impression-cylinder into sheet-receiving position at each sheet-gripping movement of the grippers thereon, whereby the gripper means on the impression-cylinder are brought into registering relation with the stop-gage for the sheets being printed at each revolution of the impression-cylinder, and quick recession of the impression-cylinder is caused, upon tripping of the impression-cylinder, immediately after the proper gripping of the sheet by the grippers, so as to quickly withdraw the tympan portion of the impression-cylinder from the printing surface, whereby a maximum amount of tympan-surface about the impression cylinder is capable of being provided and employed in printing, and, further, to provide novel means whereby the impression-cylinder is moved into sheet-receiving position at each sheet-gripping movement of the grippers thereon whether the control for the position of the impression-cylinder is in tripped or in untripped relation.

It is the object of my invention further, to provide a tripping mechanism comprising a pair of latched members, one of which is arranged to be automatically placed in unlocking position, and the other of which is under control of the operator; further, to correlate the moment of automatically placing one of the latched members in unlocking position with the moment of sheet-taking by the gripper mechanism; and, further, to provide means under the control of the operator for maintaining the manually

controlled latch-member in unlatching relation.

The invention will be further readily understood from the following description and 5 claims, and from the drawings, in which latter:

Figure 1 is a front side elevation of so much of a printing press as is necessary to illustrate my invention.

10 Fig. 2 is a rear side elevation of the same.

Fig. 3 is a section of the same, taken in the plane of the line 3—3 of Fig. 4.

Fig. 4 is a plan view of the same, partly broken away.

15 Fig. 5 is a section, taken on the line 5—5 of Fig. 4, showing the operating means for the sheet-grippers and the stop-gage for the sheets.

Fig. 6 is an axial section of a detail of the 20 mounting for one end of the impression-cylinder, taken in the plane of the line 6—6 of Fig. 7; and

Fig. 7 is a cross-section of the same, taken in the plane of the line 7—7 of Fig. 6.

25 Fig. 8 is a side-elevation showing a detail of the latching means for the impression-cylinder, with the latching parts in position for coacting relation.

30 11 represents the main frame of the machine, in which an impression-cylinder 12 is rotatably mounted. The impression-cylinder co-operates with suitable type or printing plates, which may be either mounted flatwise, for instance on a reciprocating carriage, or on a rotatable cylinder or 35 cylinders. I have exemplified a plurality of plate-cylinders 13, of which one or more may be employed having suitable printing plates indicated at 16 in Fig. 5, suitably secured thereto. The plate-cylinders are suitably journaled in the main frame, as in 40 bearings 14. Suitable inking mechanism is provided for each of the plate-cylinders, as instance by the inking rollers 15.

45 The impression-cylinder is provided with gudgeons 17, exemplified as eccentrically journaled in bushings 18 at the respective ends of the cylinder, rockable in bearings 19 in the main frame.

50 The impression-cylinder is exemplified as comprising an impression-part 21, and a sunken part 22, at the periphery of the cylinder, (see Fig. 5), the sheet to be printed being arranged to be received across 55 the impression or tympan part of the cylinder, and the sunken part being provided to pass the plate-cylinders without contacting with the printing surfaces. The impression-part is exemplified as extending 60 throughout the greater part of the circumference of the impression-cylinder.

I have provided means whereby the impression-cylinder is normally in unprinting or off-impression relation. I have also pro-

vided means, under control of the operator 65 during operation of the machine, whereby the impression-cylinder is maintained in printing relation. I have further provided means whereby the impression-cylinder at each revolution thereof, whether in printing or off-impression relation, is placed in sheet-taking position, whereby the grippers mounted on the impression-cylinder are brought into definite relation to the stop-gage for the edge of the paper for properly 70 taking and gripping the sheet which may be against the stop-gage.

I have further provided means whereby the latter devices comprise a latch which is automatically placed in unlatching relation 80 proximate to the moment of the location of the impression-cylinder in sheet-taking position.

This moment of automatic release of the latch and the moment of sheet-taking relation of the grippers, are proximate or substantially coincident, so that proper taking of the sheet is assured and the sheet caused to travel past the plate-cylinder or cylinders, throughout its path of travel, either in 90 on-impression or in off-impression relation, so that if the impression-cylinder is in off-impression relation, contact of the sheet with any part of the printing surfaces is avoided, and for further insuring that when 95 the sheet is to travel in on-impression position it shall travel in this relation throughout its entire path past the printing surfaces.

Exemplifying a structure for accomplishing 100 these purposes, the bushings 18 have arms 25 rigid therewith. A rock-shaft 26 is journaled in bearings in the main frame and has arms 27 fixed thereon. Links 28 connect the arms 25 and 27, at the respective 105 sides of the machine, with which they are respectively articulated by articulations 29 and 30. The links are extensible by means of the threaded connections 31 therein.

An arm 32 is rigid with the rock-shaft 26, 110 and coacts with a cam 33 rotating in unison with the impression-cylinder. The arm 32 carries an anti-friction roller 34, which is arranged to bear on the cam when the parts are in coactive relation. The cam 33 has an 115 axis of rotation instanced as coincident with the axis of a stud-shaft 163, journaled in a bearing in the main frame. A gear 36 is fixed on a shaft 35. A drive-pinion 37 meshes with the gear 36 and with a gear 38 on a shaft 39 journaled in a bearing in the 120 main frame. A gear 40 is also fixed to said shaft and meshes a gear 41 which rotates the impression-cylinder. The plate-cylinders are provided with gears 42 meshing with the gear 41 for rotating the plate-cylinders in unison with the impression-cylinder. 125

The cam 33 comprises a low portion 51, a high portion 52, and preferably an apex resting portion 53. The low portion extends throughout the greater portion of the cam, 5 the high portion having comparatively abrupt climbing and receding faces 54, 55, for causing comparatively abrupt approach and recession of the impression-cylinder with relation to the plate-cylinders, for the 10 purpose hereinafter explained.

The roller 34 is normally urged into contact with the cam so as to normally coact with the low portion 51 of the cam, accomplished by means of a spring 56 shown 15 encircling a rod 57, slideable in a bearing 58 pivoted in a lug 59 of the frame. The rod is articulated at 61 with an arm 62 fast on the rock-shaft 26. The tension of the spring is adjusted by means of a nut 63, locked in 20 place by a jam-nut 64 received about the threaded end 65 of the rod.

The spring normally urges off-impression relation of the impression-cylinder, but at 25 each revolution of the cam the impression-cylinder is moved for causing its grippers 68 to move into definite relation with positioning means for determining the sheet position, exemplified as stop-gages 69, so as to insure a definite relation between the grippers and stop-gages for insuring proper taking and gripping of each sheet fed against the stop-gages, so as to insure proper printing of the sheet if the impression-cylinder is in on-impression relation; and proper 30 delivery of the sheet to suitable delivery mechanism whether the impression-cylinder is in on-impression or off-impression relation. Such delivery mechanism is exemplified as a transfer-roll 71, provided with delivering 35 grippers 72 which take the sheet upon release thereof by the cylinder-grippers and feed the same away from the impression-cylinder meditately or immediately to sheet-delivering position. The latter mechanism 40 may be of usual construction and is not therefore more particularly shown.

If it is desired to maintain the impression-cylinder in printing or on-impression relation, the roller 34 is maintained out of 50 contact with the low portion of the cam, accomplished in the present instance by a latch, comprising a latch-member 81, controlled automatically by the mechanism of the machine, and a latch-member 82 which is manually controlled. The latch is provided with retaining means, comprising a tongue 83 on one of said members received in a groove 84 on the other of said members, for retaining the members in coacting 55 relation.

At each rotation of the cam, the apex-portion 53 of the cam contacts the roller 34, whether the impression-cylinder is in printing relation or in off-impression relation, in 60 order to automatically move the latch-mem-

ber 81 sufficiently to permit release of the manually controlled latch-member 82, when the latter is being urged toward releasing position, as hereinafter described.

The release of the retaining members of 70 the latch takes place proximate to the moment of coaction between the impression-cylinder grippers and the stop-gages, and preferably just subsequent to the gripping of the sheets by the grippers. There is pref- 75 erably a slight dwell or concentric face on the cam at its apex-portion so as to maintain the impression-cylinder momentarily in extreme approach toward the plate-cylinders for permitting completion of action of 80 the sheet-taking grippers and release of the latch, at a moment slightly prior to arrival of the advance edge of the sheet opposite the printing surface on the first plate-cylinder. This extreme approach of the im- 85 pression-cylinder toward the plate-support, that is, toward the stop-gage 69, is caused by the rocking of the eccentric bearings 18 by the apex-portion 53 of the cam, placing 90 said eccentric bearings in the present instance in radial positions, differing from the radial positions of the same when the impression-cylinder is in either the on-im- 95 pression relation or the off-impression relation hereinbefore mentioned, and causing 100 rotation of said impression-cylinder in a rotary path which differs from the rotary paths of the same when said impression-cylinder is in either of said on-impression or off-impression relations. If the impres- 105 sion-cylinder is to be moved into off-im- 110 pression relation the abrupt receding face 55 of the cam permits the recession to be accom- 115 plished quickly, but without jar.

The latch-member 82 is fast on a rock- 105 shaft 86 journaled in bearings in the main frame. The shaft also carries a double arm 88, 89, fixed thereon, springs 91, 92, coact- 110 ing with the respective arms. The spring 91 is received about a rod 93 articulated at 94 to the arm 88 and arranged to bear against the bearing 95 pivoted in the frame through which the rod passes, and a collar 96 adjustably fixed to the rod by a set- 115 screw 97.

A rod 101 slides in a bearing 102 on the arm 89, and is articulated at 103 with a rocker-bar 104. The spring 92 encircles the rod and is received at one end against the bearing 102 and at its other end against a 120 collar 106 adjustably fixed to the rod by a set-screw 107. A stop 108 limits the retraction of the rocker-bar 104.

The rocker-bar rocks on a stud-shaft 111 journaled in a bearing of the frame. It is 125 provided with a dog 113 arranged to be engaged by a keeper 114 on a lever 115, pivoted on a stud 116 in a bearing of the main frame. The lever is provided with arms 118, 119, 120. A spring 121 acts on 130

the arm 119 for normally urging the keeper into the path of the dog 113. The spring is received about a rod 122 articulated at 123 to the arm 119 and slidably in a bearing 124 pivoted to the frame; the spring being located between said bearing and a collar 125 adjustably fixed to the rod by a set-screw 126.

10 A pedal 130 is on a rod 131 received through a bearing 132 in the platform 133, and is articulated at 134 to the arm 120 of the lever 115.

15 A pedal 136 is on a rod 137 received through a bearing 138 in the platform and articulated at 139 with the rocker-bar 104.

20 When the pedal 130 is depressed, the keeper 114 is brought out of range of the dog 113 which, by the action of the spring 92, is moved out of range of the keeper, 25 the spring causing movement of the rocker-bar, the stop 108 limiting said movement. When the foot is taken off the treadle 130 the keeper returns to normal position, ready to engage the dog when the latter is again brought within its range.

30 The release of the dog for on-impression relation of the impression-cylinder causes extension of the spring 92 and brings the double arm structure 88, 89, under the moving influence of the spring 91, for causing torsional strain in the shaft 86 and applying force upon the latch-member 82 to urge the same into range with the latch-member 35 81. A stop 90 limits the movement of the latch-member 82 in such coactive relation. The movement of the latch-member 82 in the opposite direction, that is to say, into off-impression relation, is restrained by the retaining members 83, 84, until the roller 40 34 is contacted by the apex-portion 53 of the cam 33. This contact causes automatic movement of the latch-member 81 away from the latch-member 82, sufficient to release the retaining connection 83, 84, between the same, thereby permitting the force being applied by the spring 91 to be effective in moving the latch-member 82, thereby permitting the roller 34 to follow the receding portion 55 of the cam to the 45 50 low portion 51 thereof, for placing the impression-cylinder in unprinting or off-impression relation.

55 This movement can, however, take place only just prior to the arrival of the beginning of the printing or tympan portion of the cylinder opposite the printing surface of the first plate-cylinder, and subsequent to the moment of gripping action of the grippers on the impression-cylinder 60 upon the sheet. The parts are so related preferably that when the parts are positioned for off-impression relation of the impression-cylinder the movement of the roller 34 along the receding face 55 of the 65 high portion of the cam will have been of

sufficient extent, prior to the arrival of the initial end of the tympan portion of the impression-cylinder at printing relation with the first plate-cylinder, so that the impression-cylinder will have moved away from the first plate-cylinder sufficiently to avoid contact of the sheet with the inked printing surface on the first plate-cylinder.

70 The grippers 68 are adjustably fixed in the usual manner to a gripper-shaft 145, 75 journaled in suitable bearings in the impression-cylinder. The gripper-shaft has a rocker-bar 147 fixed thereon, provided with slots 148, 149. The frame is provided with a pin 151 which coacts with the slot 149 for moving the grippers into gripping position, and with a pin 150 which coacts with the slot 148 for moving the grippers into release position.

80 The stop-gages 69 are adjustably secured 85 to a rock-shaft 153 in the usual manner, the rock-shaft being provided with an arm 154 fixed thereon. A bell-crank lever 155 is pivoted at 156 to the main frame. One of the arms of the bell-crank lever 155 has a 90 roller 157 which coacts with a cam-track 158, rigid with the impression-cylinder, and the other arm of the lever coacts with the arm 154 for rocking the stop-gages into and out of stop position. The sheets may be fed 95 off a usual table 159 and the edges of the sheet rest upon usual fingers 160 coacting with the stop-gages.

100 The operation of the machine is fully described in connection with the description of its various elements. Aside from the advantages hereinbefore recited, the invention provides novel means whereby a plurality of plate-cylinders may be employed about an impression-cylinder, each of the plate-cylinders fully one-half the diameter of the impression-cylinder and having a printing surface thereon throughout its entire circumference, with the assurance that if the impression-cylinder is placed in off-impression relation that that relation shall become effective prior to arrival of the beginning of the sheet opposite the printing surface of the first plate-cylinder, for preventing printing or smudging of part of the sheet, and that if the impression-cylinder is placed in printing relation, that that relation is maintained until the sheet has entirely passed the entire printing surface of the last plate-cylinder, so as to insure entire printing of 110 the sheet, thus avoiding the spoiling of sheets, and that further, each sheet will be properly gripped for proper printing and delivery thereof.

115 The shaft 39 carries a pinion 161 fixed 120 thereon, which meshes with a gear 162 fast on a stud-shaft 163 suitably journaled in the frame of the machine, the gear 162 having the cam 33 fixed thereon, as by bolts 164. The parts are so arranged as to cause the 130

cam 33 to rotate in unison with the impression-cylinder 12.

A stop 165 limits the movement of the arm of the rocker-bar 147 in both directions.

Having thus fully described my invention, what I claim as new and desire to secure by Letters Patent, is:

1. In a printing press, the combination of an impression-cylinder having a normal sheet-taking position, and means for causing rotation of said impression-cylinder in printing relation or in off-impression relation comprising means for moving said impression-cylinder into said normal sheet-taking position at each revolution thereof in printing relation or in off-impression relation, and for moving said impression-cylinder to change its axis of rotation between said normal sheet-taking position and said printing relation and said off-impression relation.

2. In a printing press, the combination of an impression-cylinder having a normal sheet-taking position, means for causing rotation of said impression-cylinder in printing relation or in off-impression relation comprising means for moving said impression-cylinder into said normal sheet-taking position at each revolution thereof in printing relation or in off-impression relation, and for moving said impression-cylinder to change its axis of rotation between said normal sheet-taking position and said printing relation and said off-impression relation, and latching means for said first-named means comprising an automatically controlled member and a manually controlled member coacting therewith whereby to control said relations of said impression-cylinder.

3. In a printing press, the combination of an impression-cylinder having a normal sheet-taking position, and an off-impression relation and an on-impression relation differing from said normal sheet-taking position, a support for a printing-surface, means for rotating said impression-cylinder normally in off-impression relation with said support, and means under control of the operator during operation of the machine for maintaining said impression-cylinder in consecutive printing relations with said support, said means comprising means for moving said impression-cylinder into said normal sheet-taking position at each revolution thereof in printing relation or in off-impression relation with said support.

4. In a printing press, the combination of a support for a printing surface, an impression-cylinder normally rotating in off-impression relation to said support manually controlled means for maintaining said impression-cylinder in printing relation to said support, and means whereby to place said

impression-cylinder into a sheet-taking position and to cause lateral movement of the axis of rotation of said impression-cylinder between said last-named position and said respective off-impression and printing relations.

5. In a printing press, the combination of an impression-cylinder normally rotating in off-impression relation, and manually controlled means for maintaining said impression-cylinder in printing relation comprising a latch embodying an automatically controlled member and a manually controlled member, said members having locking means between them to resist manual movement of said manually controlled member, and said locking means released solely by automatic movements of said automatically controlled member.

6. In a printing press, the combination of an impression-cylinder, gripping means therefor, and means for tripping said impression-cylinder for placing said impression-cylinder in printing relation or in off-impression relation comprising means for placing said impression-cylinder in proper sheet-gripping relation differing from said other relations at each normal sheet-taking moment in its revolutions.

7. In a printing press, the combination of an impression-cylinder, gripping means thereon, sheet-gaging means, and means for placing said impression-cylinder in printing relation or in off-impression relation comprising means for placing said gripping means into the same gripping relation with said sheet-gaging means at each normal sheet-taking moment in the revolutions of said impression-cylinder and for laterally shifting the axis of rotation of said impression-cylinder between said last-named moment and said respective off-impression and printing relations.

8. In a printing press, the combination of an impression-cylinder, means for placing said impression-cylinder in tripped relation or in untripped relation for printing rotation or idle rotation of said impression-cylinder, and means for placing said impression-cylinder in exact sheet-taking position at each revolution thereof in tripped relation or in untripped relation.

9. In a printing press, the combination of an impression-cylinder, sheet-taking means thereon, sheet-delivering means, means for placing said impression-cylinder in tripped relation or in untripped relation for printing rotation or idle rotation of said impression-cylinder, and means for placing said impression-cylinder in exact sheet-taking position differing from said tripped relation and said untripped relation at each normal sheet-taking moment in its revolutions for properly taking each sheet for

registered printing thereon and proper delivery thereof to said sheet-delivering means.

10. In a printing press, the combination of a support for a printing surface, an impression-cylinder, sheet-taking means therefor, and means for placing said impression-cylinder in printing relation or in off-impression relation with said support, said means comprising a cam having an apex-portion placing said impression-cylinder in exact sheet-taking position differing from said tripped relation and said untripped relation, at each sheet-taking moment in its 15 rotations while said impression-cylinder is in printing relation and in off-impression relation, said cam comprising abrupt climbing and receding cam-faces at the respective sides of said apex-portion for quick 20 movement of said impression-cylinder into printing relation or into off-impression relation.

11. In a printing press, the combination of a support for a printing surface, an impression-cylinder having an impression-part and a sunken part about its periphery, said impression-part occupying a greater angular portion of said periphery than said sunken part, a plate-cylinder having a plate-supporting surface throughout substantially its entire circumference coacting by a single revolution thereof with said impression-part at each revolution of said impression-cylinder, rockable bushings in which said impression-cylinder is eccentrically journaled, arms on said bushings, rocker-arms having operative connections with said last-named arms, and a cam rotating in unison with said impression-cylinder for operating 40 said rocker-arms and comprising a low cam-portion and a high cam-portion, said low cam-portion extending throughout a greater number of degrees of the cam than said high cam-portion and said high cam-portion 45 having abrupt climbing and receding cam-faces for causing quick approaches and recessions of said impression-cylinder with relation to said support during rotations of said impression-cylinder.

12. In a printing press, the combination of a support for a printing surface, an impression-cylinder, sheet-taking means therefor comprising sheet-gripping grippers, rockable bushings in which said impression-cylinder is eccentrically journaled, arms on said bushings, rocker-arms, having operative connections with said last-named arms, and a cam rotating in unison with said impression-cylinder for operating said rocker-arms and comprising a low cam-portion and a high cam-portion for respectively placing said impression-cylinder in off-impression relation and in printing relation to said support, said high cam-portion having 65 an apex-portion for placing said impression-

cylinder during closing of said grippers in sheet-taking position closer to said support than during printing position of said impression-cylinder, said low cam-portion extending throughout a greater number of degrees of the cam than said high cam-portion and said high cam-portion having abrupt climbing and receding cam-faces for causing quick approaches and recessions of said impression-cylinder with relation to said support during rotations of said impression-cylinder. 70 75

13. In a printing press, the combination of a support for a printing surface, an impression-cylinder, rockable bushings in which said impression-cylinder is eccentrically journaled, arms extending from said bushings, rocker-arms having operative connections with said last-named arms, sheet-gripping means on said impression-cylinder, sheet-arresting means, and a cam for operating said rocker-arms, said cam comprising an apex-portion for placing said impression-cylinder in sheet-taking relation with said gripping means in sheet-gripping relation with said sheet-arresting means, said apex-portion of said cam provided with abrupt climbing and receding cam-faces acting to quickly move said impression-cylinder into printing relation or off-impression relation with said support, whereby the greater portion about the circumference of said impression-cylinder is employable as an impression-surface, said sheet-taking relation of said impression-cylinder differing 90 95 from said printing relation and said off-impression relation thereof. 100

14. In a printing press, the combination of a support for a printing surface, an impression-cylinder, rockable bushings in which 105 said impression-cylinder is eccentrically journaled, arms extending from said bushings, rocker-arms having operative connections with said last-named arms, sheet-gripping means on said impression-cylinder, sheet-arresting means, a cam for operating said rocker-arms, said cam comprising an apex-portion for placing said impression-cylinder in sheet-taking relation with its gripping means in sheet-gripping relation 110 with said sheet-arresting means, said apex-portion of said cam provided with abrupt climbing and receding cam-faces acting to quickly move said impression-cylinder into printing relation or off-impression relation 115 with said support, said sheet-taking relation of said impression-cylinder differing from said printing relation and said off-impression relation thereof, and latching means for said rocker-arms comprising an automatically operated latch-member and a manually controlled member coacting with the latter. 120 125

15. In a printing press, the combination of a support for a printing surface, an impression-cylinder, rockable bushings in 130

- which said impression-cylinder is eccentrically mounted, arms extending from said bushings, rocker-arms having operative connections with said last-named arms, sheet-gripping means on said impression-cylinder, sheet-arresting means, a cam for operating said rocker-arms, said cam comprising an apex-portion for placing said impression-cylinder in sheet-taking relation with its gripping means in sheet-gripping relation with said sheet-arresting means, said apex-portion of said cam provided with abrupt climbing and receding cam-faces acting to quickly move said impression-cylinder into printing relation or off-impression relation with said support, said sheet-taking relation of said impression-cylinder differing from said printing relation and said off-impression relation thereof, and a latch for said rocker-arms comprising latch-retaining members one of which has operative connection with said mechanism for being automatically controlled thereby and the other of which is manually controlled.
16. In a printing press, the combination of an impression-cylinder, eccentric bearings for said impression-cylinder, sheet-taking means on said impression-cylinder, a support for a printing surface, and means for rocking said eccentric bearings into different radial positions for on-impression, off-impression and sheet-taking relations of said impression-cylinder.
17. In a printing press, the combination of an impression-cylinder, eccentric bearings therefor, and means for moving said eccentric bearings into different radial positions for on-impression, off-impression and sheet-taking positions of said impression-cylinder.
18. In a printing press, the combination of an impression-cylinder normally rotating in off-impression relation, tripping means for locking said impression-cylinder in on-impression relation, and automatic means for automatically moving said impression-cylinder out of both said relations into sheet-taking relation.
19. In a printing press, the combination of an impression-cylinder normally rotating in off-impression relation, tripping means for locking said impression-cylinder in on-impression relation, and automatic means for automatically moving said impression-cylinder out of both said relations into sheet-taking relation, said last-named means including means for moving a movable member of said tripping means into release position.
20. In a printing press, the combination of an impression-cylinder having a normal sheet-taking position, and means for causing rotation of said impression-cylinder in printing relation or in off-impression relation comprising means for placing said impression-cylinder in said normal sheet-taking position at each revolution thereof in printing relation or in off-impression relation, said printing relation and off-impression relation being different from said sheet-taking position.
21. In a printing press, the combination of an impression-cylinder, sheet-positioning means, sheet-taking means on said impression-cylinder coacting therewith, sheet-delivering means, coacting tripper-parts for placing said impression-cylinder in tripped relation or in untripped relation for printing relation or idle relation of said impression-cylinder, and means for shifting the axis of rotation of said impression-cylinder for releasing said coacting tripper-parts and placing said sheet-taking means in coactive relation with said sheet-positioning means.
22. In a printing press, the combination of an impression-cylinder, a plate-cylinder, said plate-cylinder having a plate-supporting surface substantially throughout its circumference, said impression-cylinder being of substantially greater diameter than the diameter of said plate-cylinder and having an impression-surface throughout the major portion of its circumference, sheet-supporting means, sheet-taking means on said impression-cylinder, said impression-cylinder having a printing position, and means for moving said impression-cylinder to position of closer approach to said sheet-supporting means than said printing position at each revolution of said impression-cylinder, and means causing closing movement of said sheet-taking means while said impression-cylinder is in position of closest approach.
23. In a single revolution printing press, the combination of a plate-cylinder having a plate-supporting surface substantially throughout its circumference, an impression-cylinder of substantially greater diameter than the diameter of said plate-cylinder and having an impression-surface throughout the major portion of its circumference, for coacting with said plate-supporting surface throughout substantially the circumference of said plate-cylinder, said impression-cylinder normally rotating in off-impression relation to said plate-cylinder, and manually controlled means for maintaining said impression-cylinder in printing relation to said plate-cylinder.
24. In a printing press, the combination of a support for a printing surface, an impression-cylinder, and means for rotating said impression-cylinder and positioning the paths of rotation of said cylinder in off-impression relation and in on-impression relation to said support and for sheet-taking relation of said impression-cylinder, said rotary path of said sheet-taking relation being different from the rotary paths of said off-impression and on-impression relations.

25. In a printing press, the combination with the bodily movable cylinder normally in off-impression position, of means beyond the control of the operator for bodily and 5 actively moving the cylinder into sheet-taking position at each revolution thereof independent of any manipulation by the operator, a holding means acting under the control of the operator when the cylinder is 10 in sheet-taking position, said holding means

acting to lock the cylinder so as to rotate in on-impression relation.

In testimony whereof, I have hereunto signed my name in the presence of two subscribing witnesses.

FREDERICK H. BEROLD.
